UNITED STATES PATENT OFFICE.

HUGH W. FELLOWS, OF LOS ANGELES, CALIFORNIA, ASSIGNEE TO J. I. CASE THRESHING MACHINE COMPANY, OF RACINE, WISCONSIN, A CORPORATION.

BAG-HOLDER.

1,199,001.

Specification of Letters Patent. Patented Sept. 19, 1916.

Application filed May 25, 1914. Serial No. 840,916.

To all whom it may concern:

Be it known that I, HUGH W. FELLOWS, a citizen of the United States, and a resident of Los Angeles, county of Los Angeles, and 5 State of California, have invented certain new and useful Improvements in Bag-Holders, of which the following is a full, clear, and exact description.

The invention relates to bag-holders and 10 seeks to provide simple and effective means whereby bags may be securely but detachably held upon a filling spout or the like and which obviates the necessity of employing thereupon spikes or catches, which are 15 apt to tear the bags and injure the hands of the persons placing the bags in position.

The invention consists in the features of improvement hereinafter set forth, illustrated in the preferred form in the accompanying drawing, and more particularly pointed out in the appended claims.

In the drawing, Figure 1 is a plan view of the improved bag-holder shown attached to the end of a spout such as is usually 25 employed for delivering grain from a threshing machine. Fig. 2 is a view in elevation of the parts shown in Fig. 1. In Figs. 1 and 2, the grippers for holding the bag in place are shown in released position, 30 Fig. 3 is a view in vertical section of the parts shown in Figs. 1 and 2, with the grippers in operative position.

The improved bag-holder is mounted upon a suitable head which, in the preferred 25 form shown, is rectangular in outline and comprises opposite parallel side walls 10 and downwardly and outwardly inclined end walls 11. If desired, the head may be formed directly upon the discharge end of 40 the filling spout 12. In the form shown, the spout is provided with a flaring end portion 13 which extends within and is riveted, or otherwise suitably secured, to the upper portion of the head.

45 The grippers for holding the bag in position upon the head are mounted upon pairs of arms 14 which, as shown, are arranged on opposite sides of the inclined end walls 11 of the head and which project outwardly 50 and downwardly from the upper portion of the head. In the construction shown, these arms are formed by the downwardly bent end portions of a pair of straps 15 which are secured to the upper portions of the opposite 55 side walls 10 of the head.

A wedging, cam-shaped gripper is pivotally mounted upon the end of each arm and projects inwardly toward the adjacent inclined end wall 11 of the head and co-operates therewith to hold the bag in place. 60 As shown, the arms are provided with inwardly projecting horizontal studs 16 on which the wedging, cam-shaped grippers are mounted. Each cam gripper comprises an inwardly projecting arm 17, an upwardly 65 projecting arm 18 and an arc or cam-shaped shoe 19 upon the inner end of the arm 17. The angle between the arms 17 and 18 is preferably slightly less than a right angle and the grippers are so disposed that they 70 tend to swing by gravity to bring the shoes 19 into engagement with the opposite inclined end walls 11 of the head. The shoes 19 are provided with curved or arc-shaped working or gripping faces which are struck 75 from centers located above the centers of the pivot studs 16, so that there is a wedging action between the gripping shoes and the end walls of the head.

The grippers are shifted to release the bag 80 by means of a pair of bails 20 and 21, the arms of which are pivotally mounted at their lower ends in the supporting arms 14 and extend upwardly between the arms 18 and the ends of the shoes 19 of the wedging 85 grippers. The bail 20 is considerably longer than the bail 21 and serves as a handle for shifting the bails. The bail 21 is provided at one end with a depending crank portion 90 22 which is connected to the bail 20, preferably by a chain 23.

In the normal position of the parts, the wedging grippers rest by gravity in engagement with the opposite end faces of the head 11. The spaces between the ends of 95 the shoes 19 and the arms 18 through which the bails 20 and 21 extend, are considerably wider than the arms of the bails, so that the wedging grippers are free to swing independently to a limited extent upon the pivot 100 studs 16. For this reason, the free edges or upper end of the bag 24 may be readily slipped over the head and between the end walls and the cam or arc-shaped working faces of the gripping shoes 19. The latter 105 then drop by gravity and engage the bag, as shown in Fig. 3. Any downward pull tending to disengage the bag will tend to turn the grippers downwardly about their pivots 16 and so force or wedge the gripping faces 110

of the shoes between the pivots 16 and inclined end faces of the walls 11 to more securely grip the upper portion of the bag. In this way, any pull on the bag tending to disengage it serves to more securely hold it in place. But the gripping wedges may readily swing upwardly to release the bag and they can all be shifted simultaneously to released position by means of the connected bails 20 and 21, as shown in Fig. 2. In the extreme upward movement of the grippers shown in Fig. 2, the arms 17 thereof engage the lower outturned ends of the arms of the bail so that the latter serve as stops to limit the upward or releasing movement of the grippers. The arrangement of the bail arms between the arms 18 and shoes 19 of the grippers also serve to maintain the grippers in proper position, while permitting a limited independent movement thereof.

It is obvious that changes may be made in the details set forth without departure from the essentials of the invention as defined in the claims.

25 I claim as my invention:—

1. A bag holder comprising a head, a series of independently movable, automatically wedging grippers mounted on said head, and means loosely engaging said wedging grippers for releasing the same.

2. A bag holder comprising a head, a series of independently movable, automatically wedging grippers pivotally mounted on said head, and a series of connected devices loosely engaging said wedging grippers for simultaneously releasing the same.

3. A bag-holder comprising a head having projecting arms, a series of inwardly projecting wedging grippers pivoted on said arms and co-operating with said head to hold the bag thereon, and a series of connected pivot arms loosely engaging said grippers

for releasing the same, substantially as described.

4. A bag-holder comprising a head having projecting arms, a series of inwardly projecting wedging grippers pivoted on said arms and co-operating with said head to hold the bag thereon, and means loosely engaging said grippers for releasing the same, said grippers having smooth arc-shaped working faces and said head having outwardly and downwardly inclined faces opposed to the smooth curved faces of said grippers, substantially as described.

5. A bag holder comprising a head, a series of independently movable, automatically wedging grippers mounted on said head, and devices having a lost motion engagement with said wedging grippers for releasing the same, said releasing devices being arranged to limit the independent movement of said wedging grippers in opposite directions.

6. A bag-holder comprising a head having projecting arms at its ends, pairs of wedging grippers pivoted on said arms and projecting inwardly toward said head, a pair of bails pivoted on said head for releasing said grippers, and a connection between said bails, substantially as described.

7. A bag-holder comprising a rectangular head having inclined, outwardly flaring ends and parts projecting beyond said ends, wedging grippers pivoted on said projecting parts, extending inwardly toward the inclined ends of said head, and having arc-shaped working faces co-operating with said inclined ends, and means for simultaneously releasing said grippers, substantially as described.

HUGH W. FELLOWS.
